[57] ABSTRACT

A recirculation-type washing machine in which a high volume, low pressure centrifugal pump and a mechanically modulated nozzle replace the usual agitator, transmission gear case, associated superstructure, and drain pump in an otherwise conventional top-loading, automatic washer. The nozzle is mechanically modulated to produce a spatially unsymmetrical field of turbulence which sweeps cyclically around within the wash basket to create the required rollover and mechanical agitation of the wash load. Within an optimum range of nozzle modulation frequency, nozzle area, and flow rate, a high level of soil removal performance is achieved with substantially no tangling.

TRANSMISSIONLESS WASHING MACHINE WITH MODULATED RECIRCULATION

BACKGROUND OF THE INVENTION

Top-loading, automatic washing machines which combine the convenience of washing, rinsing, and spin extraction in a single tub with the simplicity and economy of a recirculator to replace the standard agitator are previously known. However, domestic manufacturers have been reluctant to introduce any of these prior designs to the market for a number of reasons. They tangle most wash loads, they are not competitive in soil removal performance, and, they depart so drastically in concept and configuration from the machines which the major domestic manufacturers are geared to build that the required investment to retool and to modify assembly facilities cannot be reconciled with the anticipated return.

SUMMARY OF THE INVENTION

The present invention provides a top-loading, automatic washing machine which is both capable of meeting the performance expectations of the modern consumer and at the same time is able to satisfy the practical requirements of the manufacturer and retailer. In particular, the present invention provides the consumer with a completely automatic, low-cost top-loading washer which delivers substantially the same soil removal performance as an agitator-type washer and which is non-tangling, capable of handling family size loads, and gentle to delicate fabrics. At the same time, the present invention provides the retailer and the manufacturer of conventional washers with a new washer concept which is simple, cost effective, reliable, and capable of being sold and serviced by existing personnel through existing facilities. The present invention is compatible with a majority of present-day, top-loading washing machines designs. Thus, it can be incorporated into these machines with minimal tooling expense and with little or no change to existing engineering and assembly methods.

Accordingly, it is an object of the present invention to provide an otherwise conventional top-loading automatic washing machine in which the standard agitator, gear case, associated superstructure, and drain pump are replaced by a recirculating loop comprised of a pump and a mechanically modulated nozzle.

Another object of this invention is to provide a fully automatic, top loading, recirculation-type washer capable of achieving acceptable soil removal with minimum tangling when operated with family sized loads.

Still another object of this invention is provision of a washing machine which is gentle to delicate fabrics.

A further object of this invention is the provision of a pump/nozzle arrangement which is compatible with present top-loading washing machine designs so that it may be embraced by manufacturers of conventional washers with a minimum of retooling or reconfiguration of assembly lines.

Other and further objects and advantages of the present invention will become apparent from the following description when considered in connection with the accompanying drawings and the appended claims.

DESCRIPTION OF THE DRAWINGS

FIG. 1 is a perspective view of a washing machine in accordance with a preferred embodiment of my invention.

tion, with certain parts cut away and in cross-section to illustrate structural details.

FIG. 2 is a functional diagram of the machine illustrated in FIG. 1 showing typical interrelationship of the component parts of the machine.

FIG. 3 is a vertical cross-sectional view, partly in elevation, illustrating the nozzle assembly and a typical mechanism for mechanically modulating the nozzle.

FIG. 4 is a cross-sectional view taken substantially on line 4-4 of FIG. 3 and,

FIG. 5 is a diagrammatic cross-sectional view taken substantially on line 5-5 of FIG. 3.

DESCRIPTION OF THE PREFERRED EMBODIMENT

FIGS. 1 and 2 illustrate a more or less conventional top-loading automatic washing machine of well-known manufacture incorporating the features of my invention presently to be described.

20 The basic washing machine and the apparatus of my invention is housed within a cabinet assembly 10 having a top 11 provided with a hinged lid 12. A base plate 13 is supported by a plurality of vibration-isolator suspension rods 14 depending from the top of the cabinet 25 10. Supported in a well known manner are the conventional tub assembly 16, washbasket 17 and motor 18. In place of the usual gear case, drain pump, associated superstructure, and agitator, there are located beneath the base plate 13 in depending relation, a pump 19, a lint filter 21 and a one way clutch 23, typically a sprag-clutch. Connected via duct 28a to the outlet of pump 19 is a two-way flapper valve 24 actuated by an electrical solenoid 26 through linkage 27. The function of the flapper valve 24 will be hereinafter described. Connected to the main discharge port 24a of valve 24 is a nozzle supply hose 28 which is connected to the inlet duct 29 of a nozzle assembly 31. Connected to the secondary discharge port 24b of valve 24 is a tee connector 33 having two branches. One branch is connected to an inlet bypass hose 32 and the other branch is connected via hose 94 to the outlet of a lint filter 21.

40 The nozzle assembly 31 includes a generally cylindrical nozzle tube 34 surmounted by a closure cap 36 and having an inlet duct 29, all shaped substantially as illustrated in FIG. 3. Preferably, the nozzle tube and inlet duct are integrally molded from a suitable tough material such as polycarbonate plastic. The lower end of the nozzle tube 34 opens to a mouth 38 which, preferably, has a reduced diameter in relation to that of the main body of the nozzle tube 34. An annular flanged ring 39 is suitably attached to the inner wall of the body portion 34 at a point slightly above the juncture of the duct 29 with the nozzle tube 34. Suitably bonded to a shoulder 41 on the ring 39 is a flexible diaphragm 42 which may be formed of thin stainless steel or of a suitable thickness of elastomeric material such as urethane rubber (Diisocyanate polyester). The diaphragm 42 is provided with a central aperture through which passes a nozzle support tube 43. This support tube 43 replaces the conventional washing machine agitator drive shaft and is mounted within the conventional basket drive tube 44 journaled within an upper bearing 46 and corresponding lower bearing, not shown. The support tube 43 is free to rotate relative to the basket drive tube 44 but is restricted by the bearings against axial movement. A conventional seal 47 interposed between the nozzle support tube 43 and the basket drive tub 44 pre-

vents the entrance of water into the space between these two parts. Preferably, the support tube 43 is provided with annular grooves to receive snap rings 48 and 49. A sleeve 51 is circumposed about the support tube 43 and is retained between the snap ring 49 and the flexible diaphragm 42. A gasket 52 is disposed adjacent the diaphragm 42 and is surmounted by a retainer sleeve 53, both the gasket 52 and sleeve 53 being confined by the snap ring 48. By the means above described, the nozzle assembly 31 is secured to the support tube 43 and is restrained against axial movement but is free to rock or tilt relative to the support tube 43 by reason of the flexibility of diaphragm 42.

As noted above, the nozzle support tube 43 is disposed within the basket drive tube 44 which in turn, is fixed, in a conventional manner, to the basket center post 55 by a drive block 56, a spanner nut 57 and a seal 58. The basket drive tube 44 is rotatably supported within the basket support tube 54 by an upper bearing 61 and a corresponding lower bearing, not shown. Seals 62 and 63 located adjacent to the upper and lower ends of the bearing 61 protect the bearing from water and prevent leakage of water through the space between the basket drive tube 44 and the basket support tube 54.

Disposed within the nozzle tube 43 is a drive shaft 64, the lower end of which extends below the clutch 23 and has fixed thereon a pulley 66. The shaft of motor 18 has fixed thereon a pulley 67 and a narrow gage belt 68 affords a driving connection between pulleys 67 and 66. The diameter of the pulley 67 is much smaller than that of pulley 66 to afford a speed reduction ratio of the order of 12 to 1.

Referring FIG. 3, the upper end portion of the nozzle drive shaft 64 extends above the upper end of the nozzle support tube 43 and has fixed thereon a roller crank 69. This crank includes a depending skirt portion 71 in which is received a sleeve bearing 72 to provide radial support and free rotation for the roller crank. The roller crank 69 is provided with a bifurcated lateral extension 73 which supports a roller 74, the roller being suitably journaled for free rotation. A cap member 36 is press-fitted over the upper opening of the nozzle tube 34 to enclose the roller mechanism.

The roller 74 is arranged to engage the inner surface 34a close to the upper opening of the nozzle tube 34 to the extent that it tilts the nozzle tube 34 so that its axis is not coincident with the axis of the driveshaft 64. In other words, the axis of the nozzle tube 34 is inclined from the axis of the driveshaft 64 by a small angle θ , as indicated in FIG. 3. Accordingly, there is created at the mouth 38 between the nozzle tube 34 and the basket centerpost 55 a crescent-shaped orifice 38a (FIG. 5) having a maximum width at a point 180° opposite the point of contact between the roller 74 and the inner surface 34a of the upper opening of the nozzle tube 34. It will be seen that when the driveshaft 64 is rotated, the roller crank 69 is revolved causing the roller 74 to effect a nutational motion in the nozzle assembly 31. This causes the crescent shaped orifice 38a to orbit or precess about the tub center post 55.

It will now be apparent that if a flow of water is pumped into the duct 29, as will hereinafter be described, the flow of water being discharged from the orbiting crescent shaped orifice 38a will establish a field of turbulence affecting only a portion of the basket at any instant of time. Clearly, as the roller crank 69 is ro-

tated, this field of turbulence must precess cyclically about the basket, such that in a single revolution of the roller crank 69, the nozzle flow will be directed in turn to all sectors of the basket. Accordingly, although the flow is steady in time, it is unsteady or cyclical in space within the basket. This flow and the means for creating the same are the heart of the present invention.

Referring to FIGS. 1 and 2, the motor 18 carries a pulley 78 which through belt 79 drives a pump pulley 81 and basket drive pulley 82. The motor 18 is reversible. During the wash, rinse, and drain cycles the motor 18 operates in a forward direction driving the pump 19 in the direction for which it is designed to deliver maximum efficiency. While the motor 18 runs in this direction the basket drive pulley 82 functions merely as an idler by virtue of the one-way clutch 23 which permits the pulley 82 to run freely relative to the basket drive tube 44. During spin-extraction and spray-rinse cycles the motor 18 operates in a reverse direction. In this mode the pump 19 is operating counter to its most efficient direction of rotation. However, its pumping capacity is adequate for pumping the small flows involved during these cycles. With the motor 18 operating in a reverse direction the basket drive pulley 82 rotates in the proper direction to engage the one-way clutch 23 and thus, the basket drive tube 44 receives power from the motor 18 and the basket 17 is caused to spin.

Although not essential, a second one-way clutch, not shown, may be utilized to couple the nozzle drive pulley 66 with the nozzle drive shaft 64 so as to permit a driving connection only when the motor 18 is running in the forward direction while free-wheeling when the motor is running in the reverse direction. This optional expedient affords a means of prolonging the life of the nozzle modulating mechanism, since mechanical movement of the nozzle is not required during the spin and spray-rinse cycles.

Referring to FIGS. 1 and 2, the plumbing circuit beginning with the tub drain aperture 22 includes a pump inlet tee fitting 20 which surmounts the pump 19. The pump includes an impeller 87 driven by shaft 88 on which is keyed pulley 81 driven by belt 79. A solenoid-actuated two-way flapper valve 24 is connected to the outlet of pump 19 by a duct 28a and this valve operates to direct the flow of water from the pump, either to the nozzle assembly 31 by way of hose 28 and duct 29 or to the tee connector 33. The tee connector 33 is connected at one branch to a bypass conduit 32 which connects to the pump inlet tee 20. The other branch of tee connector 33 connects to the outlet of filter 21 by way of the conduit 94. The filter 21 contains a lint screen 21a which is designed in the conventional manner to capture sand, bits of thread and the like. A conduit 84 connects the filter inlet to the outlet of check valve 93. The check valve 93 contains two flappers. A first flapper 93a admits water from the side of the tub 16 but prevents water from passing back thereto. A second flapper 93b allows water to pass to drain 97 but prevents air or water from re-entering. A solenoid 99 actuates water inlet valve 102 which is connected to the inlet supply 101 with the outlet of the valve being connected to a basket fill hose 103.

As may be seen by reference to FIG. 2, valves 24 and 102 are actively controlled by electrical solenoids while the flapper-type check valve 93 is passively controlled by suction or pressures within the system. When the solenoid 26 which controls valve 24 deenergized, the

valve is normally open to the nozzle supply conduit 28 and is at the same time closed off the tee 33. When the solenoid 99 controlling valve 102 is deenergized, that valve is closed.

OPERATION

To operate my washing machine, the user loads the laundry, adds detergent in the usual manner and actuates an automatic cycle controller of a conventional type to initiate the following sequence of operations.

STEP 1. FILL

The solenoid 99 is energized to open inlet valve 102 allowing water from the inlet supply 101 to fill the tub 16 to a level which is predetermined by a fill timer or by one of the common types of washing machine water-level switches. When the desired level is reached, solenoid 99 is deenergized to close the inlet valve 102.

STEP 2. WASH

Both of the valve solenoids 26 and 99 are deenergized so that valve 102 is closed and valve 24 is open to nozzle inlet conduit 28 and closed to the tee connector 33. The motor 18 is energized to run in a forward direction and a main flow of water enters the pump inlet via the tub drain aperture 22. Pump suction causes the inlet flapper 93a of valve 93 to open so that a secondary flow of water from the tub 16 is drawn via valve 93 through the lint filter 21. In this mode of operation the flapper 93a is open and flapper 93b is held closed by pump suction. This filtered secondary flow joins the main flow at the pump filter inlet tee 20. The full output flow of the pump 19 is directed via the two way flapper valve 24 into the conduit 28 whence the flow passes to the nozzle inlet duct 29 and from there into the space between the nozzle tube 34 and basket centerpost 55. The flow then discharges into the basket through the crescent shaped orifice 38a. While this is occurring the roller crank 69 is being rotated by the motor 18. This forces the roller 74 to rotate against the inner surface 34a of the upper end of the nozzle tube 34 which causes the entire nozzle to nutate. The nutating nozzle mouth 38 forms a rotating crescent-shaped orifice 38a with the basket centerpost 55. Water is discharged from this orifice with great force into that sector of the basket 17 faced by the crescent-shaped orifice 38a at any given instant. Because the orifice orbits the basket centerpost cyclically, all sectors of the basket 17, in turn, receive the full force of the discharge flow for each revolution of the crescent-shaped orifice 38a. This continually orbiting orifice produces within the basket a cyclic flow which is both unsymmetrical and unsteady in space but which is steady in time. Thus, articles of laundry within the various sectors of the basket are alternately subjected to bursts of intense flow followed by intervals of relative quiescence. The result is an organized and repetitious roll-over of the entire load, each article in turn receiving brief bursts of intense flow each time it passes through the discharge region of the moving orifice. This action produces the required flexing of laundry articles to provide the necessary mechanical influence for good soil removal. The circulation or roll-over of the load is self-starting and persistent, each article of laundry being moved unsteadily in a series of small "jerky" motions rather than in steady, continuous motions. The unsteady motion prevents stagnation of the load and minimizes tangling by maintaining an organized distribution of the wash load.

STEP 3. DRAIN AND BACKFLUSH FILTER

Motor 18 is momentarily deenergized and during the ensuing stoppage of flow, the solenoid 26 controlling valve 24 is energized. This moves the flapper 24c within the valve to block the outlet 24a to conduit 28 and to open the outlet 24b leading to connector tee 33. Motor 18 is again energized to run in a forward direction and the flow is now directed from the tub drain aperture 22, through the pump 19, to the connector tee 33 where part of the flow returns to the pump inlet via the bypass conduit 32 and the balance of the flow passes via the conduit 94 to the filter outlet. This flow backflushes the lint screen 21a and passes to the side check valve 93 wherein the pressure closes flapper 93a and opens 93b to permit the water to exit the machine via the drain conduit 97. This operation continues for a timed interval of sufficient duration to completely empty the tub of water and then the motor 18 and valve solenoid 26 are automatically switched off.

STEP 4. SPIN

Solenoid 26 is again energized as during the drain function described in Step 3 and the motor 18 is energized to run in a reverse direction. The clutch 23 thereby engages to transmit power from the basket drive pulley 82 to the basket drive tube 44 to spin the basket 17. Water remaining in the load is extracted by centrifugal force and is discharged to the drain via the same circuit as described in STEP 3 above.

STEP 5. SPRAY RINSE

During the spin cycle and after a predetermined time has elapsed to extract substantially all of the centrifugable water from the laundry load, solenoid 99 is energized for a short interval to open valve 102 allowing a spray of fresh water to pass through conduit 103 and impinge on the spinning laundry load. Solenoid 99 is then deenergized to cut off the spray for an interval of time sufficient for most of the water just introduced to be extracted by centrifugal force. Preferably, this spray cycle is repeated several times. After the final spray, the spin cycle continues for a predetermined time of sufficient duration to extract substantially all of the centrifugable water from the load. Thereafter, the motor 18 and solenoid 26 are deenergized. The basket 17 comes to rest and valve 24 returns to its normal state wherein it is open to conduit 28 leading to the nozzle 31.

STEP 6. FILL

The tub 16 is filled in the same manner as described in STEP 1.

STEP 7. RINSE

The solenoids 26 and 99 are deenergized and the motor 18 is energized to run in a forward direction. The ensuing operation is identical to that occurring during the wash function.

STEP 8. DRAIN

The components are actuated to repeat the cycle as described above in STEP 3.

STEP 9. SPIN

The spin function as described above in STEP 4 is repeated.

STEP 10. SPRAY RINSE

The spray rinse function as described above in STEP 5 is repeated.

STEP 11. FINAL SPIN AND SHUT OFF

After the final spray, the spin cycle continues for a predetermined time of sufficient duration to centrifuge as much as possible of the remaining water from the

load. Thereafter, the motor 18 and solenoid 26 are de-energized, the basket 17 comes to rest and the laundry cycle ends.

DESIGN PARAMETERS FOR OPTIMUM PERFORMANCE

Experimental evidence demonstrates that an optimum nutational frequency exists wherein soil removal is maximized and tangling is minimized.

When the nozzle modulation frequency is zero, the wash load circulates sluggishly or stagnates completely. Certain articles reside for long periods near the nozzle orifice and become relatively clean while soil removal in articles further removed from the orifice is very poor. The articles near the orifice frequently twist and tangle severely in this mode of operation.

When the nozzle modulation frequency is increased, a transition in the behavior of the wash load occurs at a frequency generally in the range between 20 and 50 cycles per minute; the wash load spontaneously begins to circulate or roll within the basket in an organized and continuously repetitive manner. However, tangling is quite severe at this incipient rollover point generally soil removal is poor also.

As nozzle modulation frequency is increased further to the range between 50 to 170 cycles per minute tangling decreases and soil removal improves enormously becoming controlled by hydraulic power at the nozzle orifice (as determined by the product of the volumetric flow rate times the nozzle orifice pressure drop.). Within that range it has been found that a nutational frequency between 125-140 cycles per minute produces good soil removal with negligible tangling.

If the nutational frequency is raised above this optimum, tangling decreases further but soil removal falls off somewhat (with nozzle power held constant). Thus any attempt to operate at nozzle modulation frequencies above the optimum requires greater nozzle power to maintain satisfactory soil removal.

In particular, within a common 15 gallon washing machine basket having a basket centerpost 2.50 inches in diameter, excellent results may be had with a nozzle having a mouth diameter of 2.65 inches. This produces a nozzle orifice area of 0.6 square inches. Operating this nozzle orifice at a flow rate of 60 GPM requires a nozzle power of just under one-fourth HP. With a pump whose efficiency is 60 percent and with plumbing losses dissipating 20 percent of the available hydraulic power, this translates to one-half HP required to power the pump. With this flow and with a nozzle modulation frequency of 134 cycles per minute, soil removal using the industry standard 5 pound mixed cotton load is within 90 percent of that which can be achieved by a standard agitator mechanism operating in the same washing machine with the same load, detergent concentration, water temperature, and wash time. This preferred configuration is capable of handling standard mixed cotton loads up to 6 or 7 pounds dry weight with negligible tangling.

Various changes coming with in the spirit of my invention may suggest themselves to those skilled in the art; hence, I do not wish to be limited to the specific embodiments shown and described or uses mentioned, but intend the same to be merely exemplary, the scope of my invention being limited only by the appended claims.

I claim:

1. In a top-loading automatic clothes washing machine, in combination, a tub adapted to contain a body of liquid, a cylindrical basket within said tub, mechanically modulated nozzle having an inlet duct and an outlet orifice, said outlet orifice being disposed below the surface of the body of liquid when the same is contained in the tub, a recirculating pump connected to said tub and said inlet duct, means for driving said pump, means for cyclically modulating the geometry of said orifice so as to direct into said body of liquid a flow of liquid which is spatially unsteady thereby creating in the body of liquid within said basket an unsymmetrical field of turbulence which sweeps cyclically around the interior of the basket in synchronism with the frequency of modulation of the nozzle.
2. In a top-loading automatic washing machine, in combination, a tub adapted to contain a body of liquid, a cylindrical basket within said tub, a vertical post disposed centrally of said basket, a nozzle having an upper inlet and a lower outlet and circumscribed about said post with the internal diameter of said nozzle being greater than the external diameter of the post, means for supporting said nozzle on said post for nutational movement in relation to said post, means for effecting nutational movement of said nozzle whereby the outlet is disposed eccentric to said post to provide a non-symmetrical discharge orifice which precesses about the axis of said post, a recirculating pump, conduits connecting said pump with said inlet and said tub, drive means for driving said pump to continuously pump liquid from the tub to said inlet for discharge through said orifice to create in the liquid within the basket a field of turbulence which is spatially unsymmetrical and which sweeps cyclically around the basket.
3. The invention as defined in claim 2 in which the means for effecting nutational movement of the nozzle comprises a drive shaft rotatably supported within the post and a roller cam eccentrically fixed on said shaft and engageable with the upper end of said nozzle.
4. The invention as defined in claim 2 in which the means for supporting the nozzle on the post comprises a flexible diaphragm connectably joining said post to the inner surface of said nozzle.
5. The invention as defined in claim 2 in which the orifice is generally crescent shaped.
6. The invention as defined in claim 2 wherein for each cycle of said orifice the field of turbulence is directed cyclically to each sector of the basket.
7. In a top-loading automatic clothes washing machine, in combination, a tub adapted to contain a body of liquid, a cylindrical basket within said tub, a mechanically modulated non-rotating nozzle supported for nutational movement about a vertical axis and having an inlet duct and an outlet orifice, a recirculating pump connected to said tub and said inlet duct, means for driving said pump, means for cyclically modulating the geometry of said orifice so as to direct into said body of liquid a flow of liquid which is spatially unsteady thereby creating in the body of liquid within said basket an unsymmetrical field of turbulence which sweeps cyclically around the interior of the basket in synchronism with the frequency of modulation of the nozzle.
